UNITED STATES PATENT OFFICE

2,385,826

MEANS FOR STOPPERING AND OPENING FLUID CONTAINERS

Anders Mathisen, Isleworth, England, assignor to
Graviner Manufacturing Company Limited,
Isleworth, England, a British corporation

Application December 2, 1943, Serial No. 512,666
In Great Britain December 18, 1942

8 Claims. (Cl. 169—31)

This invention relates to stoppering devices for fluid containers, particularly for storing fluid under pressure. The containers may be used for storing fire extinguishing liquids under gas pressure.

The invention is applicable for example to stoppering devices as described in Patents Nos. 2,143,132 and 2,143,133 issued to H. M. Salmond on January 10, 1939.

Stoppering devices of the kind described in Patent No. 2,143,132 are opened most satisfactorily by explosive charges of the kind herein described. However, in some cases it may be necessary to make provision for opening the stoppering device by hand-operated means, for example, when the explosive charge has failed to operate, or more especially in cases where the electrical ignition system has become disabled, particularly in connection with military operations.

In Patent No. 2,143,133 a stoppering device for fluid containers is shown in the form of a plug having a recess or bore formed in one end thereof and a stem at the other end, this stem being connected to the plug by a thin rim of the material of the plug. The stem is surrounded by a sleeve which is formed in the plug by forming a groove in the plug concentric with the stem. The stem is preferably of slightly smaller diameter than the recess or bore, while a nut or screwed sleeve is screwed on the stem so as to confine a small amount of explosive substance in the space between the stem, the sleeve, the bottom of the groove and the nut.

To explode the explosive substance a fuse element is mounted in the stoppering device which, when energised by an electric current, ignites the explosive substance to fracture the thin rim of material connecting the stem to the plug, whereby the stem and nut are ejected so as to enable the fluid to be discharged from the container.

It is the object of the present invention to provide a stoppering device, for the purpose described, with hand operated means for fracturing the stem.

In Patent No. 2,236,961 is described a stoppering device provided with manually operated means for fracturing a hermetic seal and for manually closing the container after a predetermined amount of fluid has been discharged from the container.

According to the present invention a stoppering device is provided for fluid containers, particularly for storing fluid under pressure, wherein a plug is provided at one end with a bore ex-

tending almost completely therethrough, while a stem extends from the opposite end of the plug, the stem being connected to the plug by a narrow rim of metal and being of slightly smaller diameter than the bore, the stem being surrounded by a concentric sleeve formed integral with the plug, and is characterised in that the stem is screw-threaded externally and receives an internally screw-threaded sleeve engaged by a screw-threaded bolt or like device passing through a fitting secured to the plug.

The invention will now be described by way of example with reference to the accompanying drawing, wherein—

15 Figure 1 shows an elevation of a stoppering device according to the present invention.

Figure 2 is a vertical section of Figure 1.

Fig. 3 is a detail horizontal section of the free end, shown broken off, of the connecting terminal block, taken on the line 3—3 of Fig. 2.

20 As shown in the drawing, a stoppering device is provided with a plug 1 of which the lower externally screw-threaded portion 2 is adapted to be screwed into a fluid container 3, preferably containing fluid under pressure, a suitable washer 5 is preferably provided between the plug 1 and the container 3.

The lower end of the plug 1 is provided with a bore 4 extending substantially completely therethrough.

30 The upper end of the plug 1 is machined to form a sleeve 6 which is bored out so as to leave a central stem 7 integral with the plug 1 at a narrow rim of metal 8. As will be seen in the drawing, the bore 4 is of larger diameter than the stem 7, as a result of which the material of the rim 8 is capable of being severed in shear when tension is applied to the stem 7.

Around the stem 7, which is screwed externally, 40 is provided an annular groove 9 for the reception of an explosive substance 10, which is confined in the groove 9 by a sleeve 11.

An electrically energised fuse device 12 is mounted in the plug 1 and is connected to an electric current supply by a plug device 13 in an insulating block 14.

45 The part of plug 1 adjacent block 14 is hexagon, and a mounting piece 14—a which may be of metal is interposed between the hexagon and the block 14, for firm support. The fuse device 12 comprises a high resistance wire coil 31 which heats adjacent ignitable material 32 which acts through lateral bore 33 extending through plug 1 to groove 9 containing explosive 10.

50 The sleeve 6 is screw-threaded externally and

a hollow connecting fitting 15 is secured to the sleeve 6 by means of the screw-thread. The connecting fitting 15 comprises a chamber 16 into which the stem 7 and the sleeve 11 can be blown by the explosion or by the escaping gases after the rim 8 of material has been fractured and the bolt 18 forced upwardly, said chamber 16 having an outlet 17 which is screw-threaded externally to take pipe union nuts and fittings so as to permit discharge of the fluid through piping at any desired point. At the time of the explosion, the bolt 18 is displaced upwardly until sleeve 11 abuts against the upper wall or ceiling of chamber 16.

A screw-threaded bolt 18 or like device engages with the sleeve 11 and extends, for example, through a packing gland or other device 19 through the connecting fitting 15 so that by rotation of the bolt 18, for example by engagement of the hexagon or otherwise shaped head 20 on the bolt 18, externally to the fitting 15, a pull is exerted upon the stem 7 causing fracture of the rim 8 of material connecting the stem 7 to the plug 1.

To rotate the bolt 18 is a spanner device having a handle 21 is fitted to the top of the connecting fitting 15 which for this purpose is provided with a boss 22 over which is fitted a sleeve extension 23 of the spanner device so as to rotate freely thereon. To the fitting 15 is secured an inverted L-shaped rim 24 which overlaps a flange 25 on the extension 23 to obviate detachment of the spanner from the connecting fitting 15.

It is found desirable to provide locking means to obviate accidental rotation of the spanner device and to this end a hole or orifice is provided in the extension 23 of the spanner device and in the rim 24 so that a pin or other like locking device 26 can be passed through said holes when in register.

A stoppering device as above described enables a container, to which it is fitted to be discharged by electrical ignition or by hand operation by the simple action of moving the handle 21. The pitch of the screw of the bolt 18 is preferably steeper than the screw of the stem 7, the pitches being preferably in such relation that the stem 7 is broken off when the spanner device is moved through an arc of approximately 45° to 90°. The screw of the bolt 18 is preferably of the opposite hand to the screw of the stem 7.

To obviate the necessity for too large an angle of movement of the handle 21, the screw thread by which the bolt 18 engages the sleeve 11 secured to the stem 7 may be of the square type having a moderate lead, and to reduce frictional effects it is desirable to insert friction reducing means such as a roller bearing or the like between the hexagon or otherwise shaped head 20 of the bolt 18 and the top of the gland device 19 in the connecting fitting 15 upon which the head 20 of the bolt 18 takes a bearing when this is rotated.

By rotating the bolt device by means of said spanner, a pull is exerted upon the stem 7 whereby fracture of the thin rim 8 of material at its root is caused, the pressure of the fluid thereafter forcing the stem 7, sleeve 11 and bolt 18 away from the opening produced in the plug 1 at the end of the bore 4. The chamber 16 in the connecting fitting 15 is of sufficient size to permit discharge of fluid through the outlet 17 without causing constriction and the bolt 18 is forced through the packing gland 19 for a sufficient distance to permit free discharge of fluid through the sleeve 6 surrounding the stem 7.

Having thus fully described my invention, what I claim as new and desire to protect by Letters Patent is:

1. A stoppering device for the purpose described, comprising a plug, said plug having an axial bore therein extending substantially therethrough from one end thereof, an externally screw-threaded stem extending co-axially from the other end of said plug, said stem being of slightly smaller diameter than said bore and being connected to said plug by a narrow rim of metal, an annular sleeve integral with said plug, said sleeve being arranged concentrically to said stem, an internally screw-threaded sleeve engaged at one end by said stem, a screw-threaded bolt engaging the other end of said internally threaded sleeve, and a fitting having an outlet therein, secured to said plug, said fitting having an opening in the end thereof remote from the plug through which said bolt passes.
2. A stoppering device for the purpose described, comprising a plug, said plug having an axial bore therein extending substantially therethrough from one end thereof and an externally screw-threaded stem extending co-axially from the other end of said plug, said stem being of slightly smaller diameter than said bore and being connected to said plug by a narrow rim of metal, an annular sleeve integral with said plug, said sleeve being arranged concentrically to said stem, said sleeve being screw-threaded externally, an internally screw-threaded sleeve engaged at one end by said stem, a screw-threaded bolt engaging the other end of said internally threaded sleeve, a fitting having one end internally screw-threaded and engaging said screw-threaded concentric sleeve by said screw-threaded end, said fitting having an opening in its other end through which said bolt passes, and a spanner device rotatably mounted on said fitting and engaging said bolt.
3. A stoppering device according to claim 2, including packing means, such as a gland in said fitting, said bolt passing through said packing means, and a shaped head on said bolt engaging said spanner device.
4. A stoppering device according to claim 2, including a boss on said fitting, a sleeve on said spanner device, said sleeve fitting over said boss, a flange on said sleeve, and an L-shaped rim secured to said fitting and overlapping said flange.
5. A stoppering device according to claim 2, including a boss on said fitting, a sleeve on said spanner device, said sleeve fitting over said boss, a flange on said sleeve, and an L-shaped rim secured to said fitting and overlapping said flange and locking means for preventing relative movement between said sleeve and said boss.
6. A stoppering device according to claim 2, including a boss on said fitting, a sleeve on said spanner device, said sleeve fitting over said boss, a flange on said sleeve, and an L-shaped rim secured to said fitting and overlapping said flange and flange having registering holes therein, and a pin engaging said registering holes.
7. A stoppering device according to claim 2, wherein the pitch of the screw-thread of the bolt is steeper than the screw-thread of the stem, the screw-thread of the bolt being of opposite hand to the screw-thread of the stem.
8. A stoppering device for fluid containers, particularly for fluid under pressure, comprising a plug having one end thereof screw-threaded externally, said plug having an axial bore in said threaded end extending almost completely there-

through, a stem extending co-axially from the other end of said plug, said stem being screw-threaded externally and being of slightly smaller diameter than said bore, said stem being connected to said plug by a narrow rim of metal, an annular externally threaded sleeve integral with said plug, said sleeve being located at the same end of said plug as said stem and being arranged concentrically to said stem and in spaced relation thereto, said plug having an annular groove therein around said stem, said groove being adapted to receive an explosive, said plug having a lateral bore therein leading to said groove, said lateral bore being adapted to receive an ignition device, an internally screw-threaded sleeve receiving said stem, said internally threaded sleeve being adapted to close said groove, a fitting internally screw-threaded at one end, said fitting be-

ing screwed on said concentric sleeve, a boss at the other end of said fitting, a packing gland in said boss, a bolt passing through said gland and engaging the other end of said internally threaded sleeve, a hexagon head on said bolt, a spanner device rotatably mounted on said boss, said spanner device having a hexagon hole therein for engagement with said head, said spanner device including a handle, a sleeve fitting over 10 said boss and a flange on said last mentioned sleeve, an L-shaped rim secured to said fitting, said rim overlapping said flange so as to prevent detachment of the spanner device while allowing same to turn on said boss, said flange and said 15 L-shaped rim having registering holes therein, and a pin engaging said registering holes.
